UNITED STATES PATENT OFFICE.

WILLIAM M. AMMERMAN, OF NEW HAVEN, CONNECTICUT, ASSIGNOR TO THE EDWIN J. TOOF COMPANY, OF NEW HAVEN, CONNECTICUT, A CORPORATION OF NEW JERSEY.

LOOPER MECHANISM FOR SEWING-MACHINES.

No. 863,490.

Specification of Letters Patent.

Patented Aug. 13, 1907.

Application filed October 22, 1904. Serial No. 229,628.

To all whom it may concern:

Be it known that I, WILLIAM M. AMMERMAN, a citizen of the United States, and a resident of New Haven, in the county of New Haven and State of Connecticut, 5 have invented certain new and useful Improvements in Looper Mechanisms for Sewing-Machines, of which the following is a specification.

This invention relates to improvements in that class of sewing machine employing a rotary looper in the 10 form of a hook that is supported and carried directly by its driver independent of a supporting race-way, and while the improvements forming the subject-matter of my present application may be applicable generally to different types of sewing machines, they have been applied in the present case to a lock-stitch looper mechanism that is particularly adapted to be used interchangeably with a chain-stitch looper for rendering a machine capable of making either a lock or chain - stitch; a 15 type of such machine and one to which my present improvements are specially applicable being disclosed in another application of mine filed of even date herewith and bearing Serial No. 229,627.

In the machine forming the subject-matter of my said other application, a rotary driving shaft at the under side of the bed-plate is provided at its forward end with a head or disk having an opening or socket in its front side for the detachable connection therewith of either a chain-stitch looper or a lock-stitch looper, the said chain-stitch looper having been made a part of the 20 subject-matter of my said other application and the lock-stitch looper having been reserved as the subject-matter of the present application. In the construction of this lock-stitch looper or hook for interchangeable use with a chain-stitch looper, it has been one of the objects 25 of my invention to provide the same with means whereby it may be readily and conveniently connected with and disconnected from the driver by any ordinary or unskilled operator.

Another object of the invention has been to so organize and associate the looper and its normally contained bobbin-case and bobbin that such parts will retain their operative relation when the looper is disconnected from its driver and so provide for their more convenient handling.

Another object of the invention has been to so associate the bobbin with the bobbin-case that it will be retained in operative position therein without the employment of the usual latch or other retaining device at the front side of the bobbin.

Another object of the invention has been to so construct and associate the parts that a bobbin may be employed which will carry a supply of thread greatly in excess of that heretofore carried by bobbins in the same or similar type of machine.

A further object of the invention has been to so con-

struct and associate the parts that the needle-thread loop may be carried around the bobbin containing the under thread with a minimum degree of strain and friction thereon.

These objects, and others to be hereinafter referred to, are secured by the novel features of construction and combinations of parts embodying my invention as hereinafter set forth in detail and pointed out in the claims.

Referring to the accompanying drawings forming part of this specification, Figure 1 is a partial front end elevation of a sewing machine embodying my invention. Fig. 2 is a partial side elevation of the machine partly in section. Fig. 3 is a longitudinal section through so much of the machine as is shown in Figs. 1 and 2. Fig. 4 is a front end elevation of the looper 60 driver with the looper removed. Fig. 5 is a rear view of the looper driver partly in section. Fig. 6 is a rear end elevation of the looper and its contained bobbin-case with the bobbin removed. Fig. 7 is a side view of the looper and its contained bobbin-case, and Fig. 8 is a side 65 view of a chain-stitch looper that is interchangeable with the lock-stitch looper or hook for connection with the looper driver.

In the drawings, 1 indicates a portion of the bed-plate of a sewing machine having a hanger 40 at its under side in which is journaled a rotary driving shaft 13 having attached to its front end a head or disk 18 in the face side of which is formed an open socket 19 adapted to receive the attaching shank of a looper, the said shaft 13 with its attached head or disk 18 constituting a 70 looper driver. The looper shown in Figs. 1 to 7 inclusive of the drawings for connection with the said driver is what is commonly known as a hook and comprises a body portion 2 having a loop-seizing beak 3 and a central opening or chamber 4 for the reception of a bobbin-case 5, which latter is retained in operative connection with the hook in the usual manner by means of a peripheral flange 6 thereon extending into a race-way groove 7 in the wall of the said hook chamber 4 and is held in a non-rotary position with respect to the hook by means 75 of an arm 8 thereon loosely engaging a notched flange 9 on the under side of the needle-plate 10.

In accordance with my present invention, the hook is provided at its rear side with a tubular shank 20 as a means for effecting connection with the driver disk 18, 100 the said shank being adapted to be inserted into the open socket 19 of the said driver disk and be removably retained therein by a suitable locking means, such means in the present case comprising a locking-lever 24 which is pivoted at 24' on the rear side of the driver disk and arranged with one end 25 normally extending through a slot 18" in the driver disk to a position for locking engagement with the hook shank 20 in a slot 27 therein and its opposite or operating end 28 extending to a convenient position to be reached by the operator 110

adjacent to the periphery of the disk. In placing the hook in operative connection with its driver, the beveled end 20' of the hook shank 20 in being entered into the driver socket will engage with the inwardly projecting end 25 of the locking-lever 24 and force the same laterally outward whereby it will ride upon the outer surface of the shank until the slot 27 in the latter has been brought into registry with it, at which time the lever will automatically snap into the said slot under the action of a suitable spring, such as indicated at 30, and so operate to lock the hook in connection with the driver. In order that the lever may operate to hold the hook firmly in connection with the driver and against any undue movement relative thereto, it is formed with a beveled or tapering surface 25' at its point of engagement with the hook shank which operates, under the action of the spring 30, to exert a constant pressure against the said hook shank in a direction to hold some part of the hook, such as its rear wall 2', firmly against the adjacent wall of the driver, as most clearly shown in Fig. 3. As the inward pressure of the lever is yielding, under the action of its spring 30, it is thereby self-adjusting in its coöperation with the hook shank to prevent any undue looseness between the hook and driver caused by wear or otherwise.

To unlock the hook preparatory to its disconnection from the driver, it is only necessary for the operator to press inwardly upon the free end of the locking lever, which operation removes its inner or locking end from locking position in the slot 27 of the hook shank.

The described means for effecting locking connection between the hook and its driver are employed in the present case only for the purpose of retaining connection between the hook and its driver in a longitudinal direction or direction parallel with their axis, and a further means is therefore employed for the purpose of so connecting the said parts as to cause the hook to rotate with its driver; such means in the present case comprising a locking projection 35 on the inner peripheral wall of the driver socket entering a slot 36 in the hook shank 20.

In view of the detachable connection of the hook with its driver in the manner described, I have utilized such fact for the purpose of dispensing with the usual bobbin-retaining latch at the front side of the bobbin-case. This I accomplish by making both the hook and the bobbin-case open at their rear side in a position registering with the opening through the tubular attaching shank 20 of the hook as most clearly shown in Figs. 3 and 6, whereby the bobbin, indicated at 11, may be entered to or removed from its position in the bobbin-case at the rear side of the hook.

With this construction of hook and bobbin-case, the latter will preferably be provided with an inwardly turned bobbin-retaining flange or wall 12 for engagement with the bobbin at the front side thereof and suitable means will also be provided for engagement with the bobbin at its rear side so as to retain the same in operative position in the bobbin-case after the hook has been connected with its driver. The means herein shown for so engaging with the bobbin at its rear side comprises a retainer in the form of a screw 14 having a longitudinally adjustable screw-threaded connection with the hook driver at the center of its socket 19. An important feature of this retainer is the fact that it

may be adjusted relatively to the bobbin-retaining wall 12 at the front side of the bobbin-case so as to vary the space between the same to accommodate bobbins of different lengths or sizes and also provide the proper clearance space between the said retainer and the adjacent end of the bobbin for the passage of the inner side of the needle-thread loop when the latter is being carried around the bobbin by the hook in the usual manner. Another important feature of the retainer when supported relatively to the bobbin with a space therebetween for the passage of the thread loop as described, is the fact of its being rotatably movable with the supporting driver whereby it will coöperate with the oppositely located rotatably movable bobbin to insure the more ready passage of the thread loop therebetween without undue strain or friction and so permit of the use of all grades and sizes of thread without liability of breakage to the same. A further and important feature of the hook and bobbin-case being open at their rear side and the bobbin being held in operative position at its rear end by the said retainer 14 on the driver, is the fact that the absence of the rear walls of the said hook and bobbin-case provides an increased depth of chamber in the bobbin-case which enables me to employ an increased length of bobbin capable of carrying a supply of under thread greatly in excess of that usually carried by the bobbin in the same or similar type of machine.

The bobbin-case 5 at its front end projects forward of the front edge of the cast-off surface 2" of the hook and is formed with a rounded surface as shown to cause the front side of a thread loop to be readily cast thereover when received from the said cast-off surface of the hook. This rounded so-called "cast-over" wall or surface of the bobbin-case, being circularly continuous at the peripheral edge of the bobbin-case and uninterrupted by latches or otherwise, insures the free and unobstructed passage of the thread-loop thereover without undue strain or friction. The central opening at the front end of the bobbin-case which is bounded by the inner edge of the flange 12 forms a so-called "bobbin-ejecting opening" through which the bobbin may be engaged for ejection through the rear opening of the bobbin-case.

After a bobbin has been inserted to its normal operative position in the bobbin-case through the tubular shank 20 at the rear side of the hook, the end of the bobbin-thread will be passed through the open slot 36 in the said shank 20 to the threading slot 37 in the bobbin-case which leads from the rear edge of the latter to a position beneath the usual tension-spring 38, as indicated at Fig. 7. The said slot 36 in the hook shank 20 therefore serves both as a threading slot for the bobbin-thread and also as a means for effecting locking connection with the driver in coöperation with the locking-projection 35 on the latter.

In Fig. 8 of the drawings, I have shown a chain-stitch looper, designated generally by 70 and being of the same construction as that forming part of my said co-pending application, which is provided with an attaching shank 20 of the same construction as the shank 20 of the lock-stitch looper or hook whereby the said two loopers may be interchangeable for detachable connection with the driver.

1. In a sewing machine, the combination with a rotary 130

looper driver, of a rotary looper having a bobbin-case and bobbin supported therein, the said looper and bobbin-case both being open at their rear side for the insertion and removal of a bobbin to and from a position within the 5 bobbin-case, and an adjustable retainer supported in position for engagement with the bobbin at its rear side.

2. In a sewing machine, the combination with a rotary driver, of a looper having means for detachable connection with said driver and also having a bobbin-case and bobbin 10 supported therein, the said looper and bobbin-case both being open at their rear side for the insertion and removal of a bobbin to and from a position within the bobbin-case, and an adjustable retainer supported in position for engagement with the bobbin at its rear side.

15 3. In a sewing machine, the combination with a rotary driver, of a looper having means for detachable connection with said driver and also having a bobbin-case and bobbin supported therein, the said looper and bobbin-case both being open at their rear side for the insertion and removal of a bobbin to and from a position within the 20 bobbin-case, and a retainer for engagement with the bobbin at its rear side having a longitudinally adjustable screw-thread connection with the driver.

25 4. In a sewing machine, the combination with a rotary driver, of a looper detachably connected with said driver and having a bobbin-case and bobbin carried therein, the said looper and bobbin-case both being open at their rear side for the insertion and removal of a bobbin to and from a position within the bobbin-case, and the said 30 bobbin-case being provided at its front side with an inwardly-projecting bobbin-retaining flange and with an opening to permit of the entry therethrough of a finger or tool for engagement with the bobbin subsequent to the detachment of the looper and its contained bobbin-case 35 and bobbin from the rotary driver.

40 5. In a sewing machine, the combination with a rotary driver, of a looper detachably connected with said driver and having a bobbin-case and bobbin contained therein, the said looper and bobbin-case both being open at their rear side for the insertion and removal of a bobbin to and from a position within the bobbin-case, and the said 45 bobbin-case being provided at its front side with an inwardly-projecting bobbin-retaining flange and with an opening to permit of the entry therethrough of a finger or tool for engagement with the bobbin subsequent to the detachment of the looper and its contained bobbin-case and bobbin from the rotary driver, and a thread-tension device attached to the bobbin-case on the peripheral wall thereof.

50 6. In a sewing machine, the combination of a rotary driver having a looper bearing surface, a looper detach-

ably connected with said driver and having a part thereof arranged for engagement with said bearing surface of the driver and also having a locking surface arranged transversely of its axis, and a spring-pressed locking 55 device carried by the driver and having a beveled surface yieldingly engaging the said locking surface of the looper and holding the latter in constant engagement with the driver.

7. In a sewing machine, the combination with a rotary 60 driver having a looper bearing surface and also having a slot, a looper having means for detachable connection with said driver and also having a part thereof arranged for engagement with said bearing surface of the driver, and a spring-pressed locking device carried by the driver 65 and having a beveled surface for engaging with the looper within its said slot and holding the same in engagement with the driver, for the purpose set forth.

8. In a sewing machine, the combination with a rotary 70 driver, of a looper having a tubular shank for detachable connection with said driver and also having a bobbin-case and bobbin supported therein, the said looper and bobbin-case both being open at their rear side in a position coincident with the said tubular shank for the insertion and removal of a bobbin to and from a position within 75 the bobbin-case, and the said tubular shank of the looper being provided with an open transversely arranged slot for the passage therethrough of the bobbin-thread, and the said bobbin-case being provided with an open threading slot in communication with the said open slot of the 80 looper shank.

9. In a sewing machine, the combination of a rotary driver having an open socket at one end thereof provided with a locking projection on its inner peripheral wall, a looper having a tubular shank for detachable connection 85 with the driver within its said socket and also having a bobbin-case and bobbin supported therein, the said looper and bobbin-case both being open at their rear side in a position coincident with the said tubular shank for the insertion and removal of a bobbin to and from a position 90 within the bobbin-case, and the said tubular shank of the looper being provided with a transversely arranged open slot adapted to receive the said locking projection in the driver socket when the shank is entered into the latter and also being adapted for the passage therethrough of 95 the bobbin-thread.

Signed at New York, in the county of New York and State of New York, this 3rd day of October, A. D. 1904.

WILLIAM M. AMMERMAN.
